DESIGN FOR AN EARRING OR SIMILAR ARTICLE

Barbara Rest, Chicago, Ill., assignor to Mario Tanzi, Chicago, Ill.

Application August 27, 1945, Serial No. 121,670

Term of patent 14 years

(Cl. D45—9)

To all whom it may concern:

Be it known that I, Barbara Rest, a citizen of the United States and a resident of Chicago, county of Cook, and State of Illinois, have invented a new, original, and ornamental Design for an Earring or Similar Article, of which the following is a specification, reference being had to the accompanying drawing, forming part thereof.

In the drawing:

I claim:

The ornamental design for an earring or similar article, substantially as shown.

BARBARA REST.
